UNITED STATES PATENT OFFICE.

JOHN E. McNAMARA, OF PETERSBURG, VIRGINIA, ASSIGNOR TO SEWARD TRUNK AND BAG COMPANY, OF PETERSBURG, VIRGINIA, A CORPORATION OF VIRGINIA.

SELF-LOCKING DRAWER.

1,363,524.

Specification of Letters Patent. Patented Dec. 28, 1920.

Application filed April 21, 1920. Serial No. 375,608.

To all whom it may concern:

Be it known that I, JOHN E. McNAMARA, a citizen of the United States, residing at Petersburg, in the county of Dinwiddie and 5 State of Virginia, have invented certain new and useful Improvements in Self-Locking Drawers, of which the following is a specification, reference being had to the accompanying drawings.

10 This invention relates to drawers of trunks, bureaus, and like articles, and a particular object of the invention is to provide means to automatically lock a drawer from opening movement when the drawer is 15 closed.

A further object is to provide a device of this kind which is keyless and so constructed that the drawer may be opened by a proper manipulation thereof without the use of a 20 key or like implement.

A further object is to provide a construction of this character which is very simple, which may be readily applied to a large variety of different structures, and which is 25 particularly applicable to the compartment drawers of wardrobe trunks and the like.

My invention is illustrated in the accompanying drawings, wherein:—

Figure 1 is a longitudinal vertical section 30 of the upper portion of one section of a wardrobe trunk with my drawer locking device applied to the drawer thereof;

Fig. 2 is a like view to Fig. 1, but showing the manner in which the drawer is 35 locked for retraction;

Fig. 3 is a transverse section on the line 3—3 of Fig. 1;

Fig. 4 is a fragmentary perspective view 40 of the drawer compartment, the walls being broken away;

Fig. 5 is a perspective view of one corner of the drawer;

Fig. 6 is a sectional view in full size of the lower rear corner of the drawer.

45 Referring to these drawings, 10 designates an article of furniture, such, for instance, as the section of a wardrobe trunk which is provided with a drawer opening 11 defined by the top 12 of the drawer compartment, by the sides 13, and the back 14 of the compartment. Slidable into and out of the drawer compartment is the drawer 15 which is of any usual or suitable construction, but is slightly less in length than the length of 50 the drawer compartment. Attached to the

sides 13 of the drawer compartment rearward of the wall 16 which extends across the body 10 below the drawer compartment are the guides 17 which are formed of relatively thin metal and are angular in cross section, 60 these guides being attached to the sides 13 of the drawer compartment by rivets 18 or other attaching devices. The horizontal flanges of these guides are disposed slightly above the upper edge of the transverse wall 65 16, as seen in Fig. 4, and these guides are less in length than the length of the drawer compartment.

The drawer 15 on its bottom inward of the rear end of the drawer is provided with 70 downwardly projecting locking studs 19. These are shown as attached to the metallic angle strips 20 which are riveted or otherwise secured to the sides and bottom of the drawer. These locking studs 75 19 extend downward, and one face of each stud is cut away, as at 20, so as to form a head which extends forward toward the front end of the drawer, as at 21. These studs 19 are so disposed as to engage 80 the rear ends of the horizontal flanges of the supporting and guiding strips 17, as illustrated in Fig. 1. When these heads 21 engage beneath the ends of the supporting and guiding strips, the drawer may have 85 slight rearward movement but no forward movement, and the only way to open the drawer is to push it rearward and at the same time press upon the lower portion of the front of the drawer below the handle 22, 90 which forces the drawer rearward and at the same time causes the drawer to tilt upward at its rear end so that the studs escape the rear end of the supporting iron 17, and then if the drawer is drawn forward or out of the 95 compartment, these studs 19 will ride upon the upper faces of the horizontal flanges of the supporting and guiding strips 17. Under ordinary circumstances, however, and unless the secret of the drawer be known, it 100 is impossible to open the drawer, for the reason that when any attempt is made to do so by simply pulling the drawer outward, even if the drawer be initially forced back, the studs will engage beneath the rear edge 105 of the horizontal flanges of the angular strips 17 and prevent the opening of the drawer. The drawer must, therefore, be canted so as to raise its rear end before it can be pulled forward, and if the studs 19 110

be provided with the heads 21, it is obvious that the drawer must be pushed backward before it can be canted.

While this locking device has been designed with particular reference to the drawers of wardrobe trunks, yet it is to be understood that it is applicable to the locking of all kinds of drawers in bureaus, cabinets, jewel boxes, desks, and other like articles of furniture.

I claim—

1. The combination with a drawer compartment and a drawer therefor, of members projecting from the wall of the drawer compartment constituting supporting guides for the drawer and preventing the initial opening movement of the drawer from a fully closed position until the drawer is canted to escape said members.
2. The combination with a drawer compartment and a drawer therefor, of a member extending from a wall of the compartment, and a locking member attached to the drawer and engaging against said first named member when the drawer is fully inserted in said compartment to prevent the initial opening movement of the drawer but disengaging from the first named member when the drawer is canted.
3. The combination with a drawer compartment and a drawer therefor, of locking means for the drawer comprising a member projecting outward from the wall of the compartment slightly below the bottom of the drawer, and a stud projecting downward from the bottom of the drawer and normally engaging behind said member when the drawer is closed, the drawer being shiftable within the drawer compartment to raise said stud above the level of the member to permit the opening of the drawer.
4. The combination with a drawer compartment and a drawer therefor, of locking means for the drawer comprising a member projecting outward from the wall of the compartment slightly below the bottom of the drawer, and a stud projecting downward from the bottom of the drawer and normally engaging behind said member when

the drawer is closed, the stud having a head 50 projecting beneath said member when the drawer is closed and the front of the drawer is flush with the front of the compartment, the drawer being shiftable rearward in said compartment to disengage the head of the 55 stud from beneath said member and being shiftable in the compartment to raise the stud to a level above said member, whereupon the drawer may be opened.

5. The combination with a drawer compartment and a drawer therefor less in length than the length of the drawer compartment, guides projecting from the side walls of the drawer compartment and supporting the drawer, said guides terminating short of the rear end of the drawer when the drawer is in place, and studs projecting downward from the bottom of the drawer and engageable behind said guides when the front end of the drawer is flush with the 70 front end of the compartment, the drawer being vertically tiltable within the compartment to raise the studs out of engagement from behind said guides and permit the drawer to be withdrawn.

6. The combination with a drawer compartment and a drawer therefor less in length than the length of the drawer compartment, guides projecting from the side walls of the drawer compartment and supporting the drawer, said guides terminating short of the rear end of the drawer when the drawer is in place, and studs projecting downward from the bottom of the drawer and engageable behind said guides when the 85 front end of the drawer is flush with the front end of the compartment, said studs being provided with forwardly directed heads engaging beneath said guides when the front of the drawer is flush with the 90 front of the compartment but disengageable therefrom upon a rearward movement of the drawer in said compartment to thereby permit the drawer to be upwardly tilted and the studs raised above the level of the guides.

In testimony whereof I hereunto affix my signature.

JOHN E. McNAMARA.
